AUTOMATIC PNEUMATIC LIQUID FUEL
ATOMIZER FOR DIESEL ENGINESWilliam Fels, Fairhope, Ala., assignor to F S K
Manufacturing Company Inc., Baldwin County,
Ala., a corporation of Alabama

Application April 16, 1934, Serial No. 720,800

6 Claims. (Cl. 299—107.8)

This invention relates to improvements in fuel and air mixing and atomizing devices and, particularly, to a device of this character for use in connection with the fuel feed for engines of the Diesel type.

Primarily, the invention contemplates the provision of an automatic fuel mixer and atomizer with which the engine may be operated with greater economical efficiency, regardless of speed of the engine or the load imposed thereon.

Another object is the provision of a fuel feed device of this character which is of simple but durable construction.

A still further object is the provision of a fuel feed device wherein the quantity of fuel and air supplied to the mixing chamber may be varied at will, independently of the speed of operation of the engine.

More specifically, the invention provides a fuel feed device wherein the fuel and air are supplied to a mixing chamber through separate passages, the flow of said fuel and air to the chamber being controlled by a valve yieldingly held closed, but operable or movable to open position when a certain predetermined pressure is exceeded in one of said passages, usually the fuel passage.

With these and other objects in view, the invention consists in certain details of construction and combinations and arrangements of parts all as will hereinafter be more fully described and the novel features thereof particularly pointed out in the appended claims.

In the accompanying drawing illustrating the preferred embodiment of the invention—

Figure 1 is a sectional view on the line 15—15 of Fig. 2;

Fig. 2 is a top plan view of the device;

Fig. 3 is a vertical sectional view on the line 16—16 of Fig. 2;

Described generally, the device comprises a body 18 secured to the engine casting by a series of bolts 29, 30, 31, 32, the bolts having nuts 33, 34, 35, 36, applied thereto in accordance with customary practice.

In the interior of body 18, there is a mixing chamber 54 and communicating with said chamber are the fuel and air passages, the fuel passage, in the present instance, being indicated at 41, and the air passage at 48. Each passage is reduced in cross section as it approaches the mixing chamber, the fuel passage being reduced somewhat more than the air passage. The reduced portion 49 of the fuel passage is of less cross sectional area than the mixing chamber 54 so as to form a shoulder 52, while the cross sec-

tion of the reduced portion 50 of the air passage is somewhat larger than the mixing chamber so as to produce a shoulder 53. Leading from the mixing chamber 54 is a passage 55 extending to the exterior of the body 18. The exterior surface of said body is recessed as at 62 in order that a nozzle 21, shouldered as at 22, may be seated therein. Said nozzle projects through an opening 23 in the engine casting 51, the inner end of the nozzle being exposed in the combustion chamber 56. Gaskets 45, 46, may be used for securing an air-tight fit between the nozzle and the associated parts of the structure.

Fuel feed pipe 37 is connected into fuel passage 47 by means of externally screw threaded 15 connecting element 40 screwed into said passage, the pipe 37 being secured in said connecting element 40 by the threaded nut 43. Likewise, air supply pipe 38 is connected to air passage 48 by threaded connecting element 41 and nut 44. The 20 inner end of connecting element 41 is recessed, by having the bore thereof tapered, as shown in Fig. 1, to provide a shoulder for a spring 27 of the spiral type. Said spring 27 is adapted to receive a shank of valve member 24 which is 25 composed of a conical member, as shown in Fig. 1, the cross section of said tapered or conical valve being such that it will simultaneously close both the fuel and air passages by engaging the shoulders 53, 52, heretofore described. 30

Fuel is supplied through pipe 37 under pressure by the use of a timed fuel pump (not shown). In other words, until a predetermined pressure is placed upon the fuel in pipe 37, spring 27 will hold valve 24 closed but, when the engine 35 is to be placed in operation, the fuel pump is actuated so as to build up the pressure of the fuel in pipe 37 to a point in excess of said predetermined pressure, whereupon valve 24 will be unseated and fuel and air both admitted to the 40 mixing chamber 54. The air will also be under pressure and, with both air and fuel under pressure they will be violently mixed in the mixing chamber 54 from whence they will flow from the combustion chamber of the engine through passage 55 and nozzle 21. This violent mixing of the liquid fuel with the compressed air in combination with the tearing up effect of a rapid expansion of the mixture, results in the condition of the fuel in highest volatile form which, 50 properly distributed in the combustion chamber, assures complete rapid combustion.

With the present construction, the action of valve 24 is automatic by reason of the fact that it is actuated by pressure of the fuel created by 55

the timed fuel pump. This, of course, is entirely different from having the valve controlled directly by the load placed upon the engine. In other words, the quantity of fuel admitted can be governed or regulated absolutely independently of variations in engine speed or the load imposed upon the engine.

The specific design of the device is also very simple, in that the differences in the cross sectional areas of the fuel and air inlets and of the mixing chamber provide the necessary valve seats and a single valve may be used for controlling the two constituents of the fuel mixture. In the preferred construction, as shown, the two passages, one for the fuel and the other for the air, are axially alined, thus facilitating the use of a single valve member. It will be understood that the cross sectional shape of the valve member 24 may be varied to conform to the cross section of the passages and chamber, a conical valve being used where the borings in the body 18 are circular.

What is claimed is:

1. In a fuel and air mixing and atomizing device, a body having a mixing chamber therein with fuel and air passages communicating with said chamber shoulders spaced longitudinally of said passages and forming concentrically arranged valve seats in said passages at opposite sides of said chamber, a valve controlling communication between said passages and chamber, and means for yieldingly holding said valve closed on said seats against a predetermined pressure in one of said passages, whereby excessive pressure in said passage will open said valve and establish communication between both passages and said chamber.

2. In a fuel and air mixing and atomizing device, a body having a mixing chamber therein with fuel and air passages extending from opposite sides thereof, shoulders spaced axially of said passages and forming valve seats at said opposite sides of said chamber, a valve engaging both

of said shoulders to close said passages, said valve being movable axially of said passages out of contact with said seats by pressure of fuel in the fuel passage, and means for yieldingly holding said valve closed.

3. In a fuel and air mixing and atomizing device, a body having a mixing chamber therein with axially alined fuel and air passages extending from opposite sides thereof, the cross-sectional area of one of said passages being less than that of the chamber and the cross-sectional area of the other passage being greater than that of the chamber, whereby shoulders constituting valve seats are formed at opposite sides of said chamber, a tapered valve movable axially of said passages, and means for yieldingly holding said valve in contact with both of said seats.

4. In a fuel and air mixing and atomizing device, a body having a mixing chamber therein and fuel and air passages communicating with said chamber at opposite sides thereof, and a valve extending through said chamber and normally closing both of said passages, said valve being movable by pressure of fuel in the fuel passage to open both of said passages.

5. In a fuel and air mixing and atomizing device, a body having a mixing chamber therein with fuel and air passages merging into said chamber, said passages being in alinement with each other, and a slideable valve member normally extending into both of said passages and closing the same, said valve being movable to open said passages by pressure of fuel in the fuel passage.

6. In a fuel and air mixing and atomizing device, a body having a mixing chamber therein and fuel and air passages merging into said chamber at opposite sides thereof, a valve seat for each passage, and an elongated valve normally engaging both of said seats, said valve being movable to open both of said passages by pressure of fuel in the fuel passage.
